(57) **CLAIM**

The ornamental design for an exposure switch for x-ray imaging system, as shown and described.

DESCRIPTION

FIG. 1 is a perspective view of an exposure switch for x-ray imaging system showing our new design;

FIG. 2 is a front view of the exposure switch shown in FIG. 1; FIG. 3 is a rear view of the exposure switch shown in FIG. 1; FIG. 4 is a left side view of the exposure switch shown in FIG. 1;

FIG. 5 is a right side view of the exposure switch shown in FIG. 1; and,

FIG. 6 is a top view of the exposure switch shown in FIG. 1. The broken lines are included for the purpose of illustrating unclaimed portions of the exposure switch for x-ray imaging system and form no part of the claimed design.
